UNITED STATES PATENT OFFICE.

BILL G. LOWREY, OF BLUE MOUNTAIN, MISSISSIPPI.

TEETER-BOARD AND STAND THEREFOR.

SPECIFICATION forming part of Letters Patent No. 624,832, dated May 9, 1899.

Application filed May 5, 1898. Serial No. 679,843. (No model.)

To all whom it may concern:

Be it known that I, BILL G. LOWREY, a citizen of the United States, residing at Blue Mountain, in the county of Tippah and State 5 of Mississippi, have invented certain new and useful Improvements in Teeter-Boards and Stands Therefor; and I do hereby declare the following to be a full, clear, and exact description of the invention, such as will enable 10 others skilled in the art to which it appertains to make and use the same.

My invention relates to improvements in devices for the amusement of children; and it consists of an improved form of teeter-board and stand for the same, the construction and arrangement of which will be hereinafter fully described and claimed.

Referring to the accompanying drawings, in which the same parts are designated by the 20 same letters of reference throughout the several views, Figure 1 represents a side view of my device in position for use. Fig. 2 is an inverted plan view of the teeter-board. Fig. 3 represents an elevation of the stand or trestle 25 for the same looking from the right-hand side as seen in Fig. 1, and Fig. 4 is a vertical sectional view taken on the line 4 4 of Fig. 3.

A designates the beam of the trestle, which is beveled along the upper edges, as at a, and 30 may be rounded at the top, as at a'. The said beam is cut out at the top near the middle, as at A', leaving the shoulders a², and at each end of the said cut-out portion is formed a shoulder A² for the teeter-board to rest upon, 35 and the said shoulders A² are plated with metallic plates a³ to strengthen and reduce the wear upon the same.

The beam A is supported upon the legs B, which are mortised into the sides of the said 40 beam near the ends thereof, as shown by the dotted lines a⁴ in Fig. 4, and are held in place by the bolts and nuts C, passing through the said beam and legs.

The legs B are each formed in two sections 45 B' and B², one of which sections, as B², is provided with clips b at one end, which extend over the edges of the other section and are arranged to slide thereon, and the other section B' is provided with a bolt b', which 50 extends through a slot b² in the first-mentioned section B², and the said bolt is provided

with a thumb-nut b³, by means of which the two sections may be clamped together at any desired adjustment. Thus it will be seen that by loosening the thumb-nut b³ the two 55 sections may be moved one upon the other to lengthen or shorten the legs and so vary the height of the beam A.

The upper sections of the legs B are provided with slots b⁴, through which the bolts C are arranged to pass, and by loosening the nuts and the bolts C the legs may be drawn downwardly until their ends are out of the mortises a⁴, and the said legs may then be turned upon the bolts C and laid parallel with 60 and against the sides of the beam A, thus folding the device into a very small space for storing or transportation.

The teeter-board is formed in two sections D' and D², and these sections are provided at 70 their meeting ends with clips d' and d², which extend over the edges of the other sections and allow the two sections of the teeter-board to slide one upon the other, as will be readily understood.

One of the sections of the teeter-board, as 75 D', is provided with one or more holes d⁰ or with a stop to receive the bolt d³, which is arranged to extend through a slot d⁴ (shown by dotted lines in Fig. 2) in the other section D², 80 and the said bolt is provided with a nut d⁵, by means of which the two sections may be clamped together at any desired adjustment. From the foregoing it will be seen that the teeter-board may be lengthened or shortened 85 at will and clamped firmly at the desired length.

The teeter-board is provided with one or more seats E at each end thereof, and the board is reduced in width, as at d⁶, just in 90 front of the said seats, these reduced portions serving the double purpose of enabling a small child to straddle the board without inconvenience and of allowing the ends of the clips d' and d² to be removed from the sections when the said sections are slid together until the said clips reach the reduced portions. Thus the two portions may be easily separated, the bolt d³ having been previously 95 removed.

For storing or transportation the two sections of the teeter-board may be separated,

as above described, or the nut d^4 may be loosened and the two sections slid together and clamped in the shortest position.

The teeter-board is provided along its edges 5 on the under side with a series of small indentations or sockets d to rest upon the shoulders A^2 of the beam A of the trestle and prevent the board from slipping upon the said beam. By providing a number of these sockets d the fulcrum of the board may be changed 10 at will, as will be readily understood. The sockets d are preferably plated with metal, as at e , to reduce the wear on the same.

The method of operating the device will 15 be clearly understood from the foregoing, and the advantages thereof will be apparent to those skilled in the art to which it appertains.

Having thus described my invention, what I claim, and desire to secure by Letters Patent of the United States, is—

1. In a device of the character described, the combination with a beam having supports and having a portion of its upper surface cut away at a uniform depth, and curved bearing-plates secured within said cut-away portion; of a teeter-board composed of two sections overlapping at one end and adjustable longitudinally with respect to each other, clips upon the overlapping end of one section 25 engaging the other section, means for clamping the said sections together at different adjustments, concave bearing-plates secured 30

upon the under side of one of the sections of the teeter-board adapted to fit upon the convex bearing-plates upon said beam, substantially as described. 35

2. In a device of the character described, the combination with a beam having supports, and having a portion of its upper surface cut away uniformly midway of its length, and 40 curved bearing-plates secured within said cut-away portion upon the upper side of said beam, the upper surface of said bearing-plates being below the upper surface of said beam upon the sides of said cut-away portion; of a 45 teeter-board composed of two sections overlapping at one end and adjustable longitudinally with respect to each other, clips upon the overlapping end of one section engaging the other section, and an adjustable bolt working in parallel slots in said sections for clamping the said sections together at different adjustments, concave bearing-plates secured 50 upon the under side of one of said sections of the teeter-board, the said concave bearing-plates being adapted to fit upon and move over the convex bearing-plates upon said beam substantially as described.

In testimony whereof I affix my signature in presence of two witnesses.

BILL G. LOWREY.
